WET SPINNING OF TEXTILE FIBERS

Erle V. Painter, Jr., Newtonville, Mass., assignor
to Fabric Research Laboratories, Inc., Boston,
Mass., a corporation of Massachusetts

Application October 1, 1947, Serial No. 777,332

11 Claims. (Cl. 57—35)

1 The present invention relates to the preparation of textile filaments and more particularly to wet spinning of textile fibers such as cotton and rayon.

The Whittier et al. patent, No. 2,412,641, describes a process and apparatus for wet spinning in which a liquid is applied to the fibers after drafting, but prior to twisting, by keeping the front drafting rolls of the spinning frame wet, so that the roving is wetted as it passes under pressure between the front rolls. Numerous benefits result, as is described in detail in the Whittier et al. patent. The tensile strength of the yarn is significantly increased, fuzziness or beardiness of the spun yarn, resulting from loose ends of the staple fiber projecting from the yarn, is reduced, contributing to an improved appearance of the yarn, and the amount of loose lint and fly which accumulate in and about the drafting frame is reduced. However, running the front drafting rolls wet is not entirely practicable in operation on a commercial scale.

It is an object of the invention to provide a practicable, commercial process and apparatus for wetting the textile fibers in the spinning operation after drafting of the roving has been completed, and before the twist has been imparted to the yarn.

A further object is to provide a process for wetting the textile fibers before twisting without wetting any part of the drafting mechanism. Other objects and advantages of the invention will appear as the description proceeds.

In accordance with the present invention, the drafted roving is wetted after completion of the drafting operation, i. e., after the roving has left the front drafting rolls, and before twisting. The liquid is applied at a point spaced less than a staple length from the front drafting rolls, preferably at a point spaced a small fraction of a staple length from the front drafting rolls. The wetted yarn is then twisted. The apparatus of the invention takes the form of a separate attachment which can be moved out of the way when desired, as in putting up an end, or in doffing or donning, so that the apparatus does not interfere in any way with the usual operation of the spinning frame. The front drafting rolls are run dry in the normal way.

The process and apparatus of the present invention produce wet-twisted textile yarn with all the advantages referred to in the Whittier patent but without the disadvantages inherent in the use of wet drafting rolls. The strength of the spun yarn is increased some 15-20% by application of

2 water alone; by application of certain resins the strength may be increased as much as 30-40% or more. At the same time, the elongation at break is reduced to about two-thirds the corresponding elongation of similar yarn which is twisted when dry in the conventional manner. The number of free fiber ends projecting from the surface of the yarn, i. e., the fuzziness of the yarn, is materially reduced with consequent improvement in strength and appearance of the yarn and reduction of lint about the spinning frame.

An illustrative embodiment of the invention is shown in the accompanying drawing, wherein—

Fig. 1 is an elevation of the attachment in operative position on a spinning frame, showing conventional parts of the drafting frame in cross section;

Fig. 2 is a plan view of the attachment with the liquid supply tube broken away;

Fig. 3 is a rear elevation of the parts shown in Fig. 2; and,

Fig. 4 is a vertical section on line 4—4 of Fig. 3.

Referring to the drawing, the apparatus is shown as applied to a well-known type of long draft spinning frame which comprises a roll beam 2 supporting, by means of a roll stand (not shown), the back drafting rolls 4, 6, middle drafting rolls 8, 10 and front drafting rolls 12, 14.

A scavenger roll 16 is mounted below the bottom front roll 12 and operates in the usual way to take up the broken end when an end down occurs. A clearer roll 18, running in contact with the upper front roll 14, may be provided.

A strand of roving 20 is supplied to the spinning frame from a roving creel (not shown) from which it passes to the drafting rolls through a throat 22, which is carried on the traverse bar 24 and thus moved periodically back and forth over the length of the drafting rolls. The middle rolls 8, 10 operate at a higher speed than the back rolls 4, 6, so that the roving strand is attenuated in passing from the back rolls to the middle rolls. The front rolls 12, 14, likewise operate at higher speed than the middle rolls 8, 10, so that a second stage of drafting is applied to the fibers in the interval between these pairs of rolls. From the front rolls, the drafted strand 26 passes through a pigtail 28 carried on the roll beam 2, from which it passes through the traveler 29 of the spinning ring 50 mounted on the ring rail 30 and thence to the bobbin 32, on which it is wound. The twist imparted to the end of the yarn as it is wound on to the bobbin runs back along the strand 26 to the point where the strand is prevented from rotating by the grip of the front rolls 12, 14, as is well known in the art.

The attachment of the present invention includes an applicator, indicated generally at A, Fig. 1; means, including tube 34 a fixed arm 36 and a pivoted link 38, for supporting the applicator from the cap bar rod 40; a trough 42 in which the applicator may be rested in inoperative position; and a drip tray 44 for catching any excess liquid which may fall from the applicator or the yarn while the frame is in operation.

The applicator includes a center body spar 46 (Figs. 2, 3, 4) on which its other parts are supported and which is welded or otherwise suitably secured to the tube 34. The entire applicator is maintained in proper spaced relation to the front drafting rolls by means of a pair of spaced side arms 48, 50, having rounded noses 52 and 54, respectively, which engage and ride on the shanks of the rolls 12, 14, as is shown particularly in Figs. 1 and 4. The side arms 48, 50 are connected in proper spaced relationship by a transverse bar 56, preferably integral with the side arms, which overlies the front face of the center body spar 46 near its top and is permanently secured thereto by soldering, welding, brazing or in any other suitable way. The bar 56 is provided with an aperture through which tube 34 passes.

A lower strand-engaging member 58 in the form of a round bar is supported on the center body spar 46 for swinging movement toward and away from the traveling strand. In the form shown, the bar 58 is formed as a continuation of operating rod 60, which extends forwardly from one end of the bar 58 (Fig. 2) and through a supporting bar 62 which is supported at its other end on the body spar 46. At its forward end, the operating rod 60 carries a knurled knob 64 which may be turned to rotate rod 60 and thus to lower the bar 58 from its operating position, shown in Fig. 1, into an inoperative position out of engagement with the strand 26, shown in dot and dash lines in Fig. 3. With the bar 58 in this inoperative position, as the attachment may be moved into or out of its operating position shown in full lines in Fig. 1, for example for moving it into or out of its rest trough 42, shown in dotted lines in Fig. 1.

To hold the bar 58 in the proper predetermined operating position, the knob 64 is provided on its rear face with a vertical notch 66, which cooperates with a detent 68 on a leaf spring 70. The leaf spring 70 is secured to the center body spar by means of machine screws 72 and held in spaced relation to the supporting bar 62 by means of a spacer block 14. The detent 68 is fixed to the front face of the leaf spring 70 near its outer free end and thus is pressed by the spring into the notch 66 when the bar 58 is in its operative horizontal position. The operating rod 60 is held against forward movement under influence of leaf spring 70 by means of a spacer sleeve 76 secured to the inner face of the supporting bar 62 and bearing at its opposite end against a stop pin 78, passing through and fixed in the operating rod 60.

Secured to the outer low side of bar 58 is a drip guard 80 which serves to catch any liquid which may drip from the strand 26 after it has passed over the bar 58 and thus to keep the lower front drafting roll 12 and the scavenger roll 16 dry.

The drafted strand 26 after leaving the front drafting roll passes over the bar 58 and thence to the pigtail 28. Liquid is applied to the thread as it passes over bar 58 by means of a cooperating upper bar 82. The bar 82 is fastened by welding to an apron 84 (Fig. 4), which, in turn, is con-

nected to an angular arm 86. The arm 86 is carried on transverse shaft 88 whose ends are received in suitable apertures in upstanding ears 89 of a U-shaped clip whose back 90 is fastened to the lower end of the center body spar 46 by a machine screw 92. The aperture in the back 90 through which the machine screw 92 passes is preferably elongated to provide for vertical adjustment of the clip on the center body spar 46 to adjust the vertical position of the upper bar 82.

The treating liquid supplied through the tube 34 drips on to apron 84, spreads over its upper surface and flows downwardly and forwardly over upper bar 82 and on to the traveling strand 26. A guard member 94 overlies the forward part of the apron 84 to catch line from the strand and prevent its collecting on the apron 84 and interfering with proper flow of liquid to upper bar 82. Preferably, apron 84 and the guard 94 are formed from a single piece of sheet stock by cutting this to the proper shape and then folding and bending it into the desired form. The angular arm 86 carries a rearwardly-extending counterbalance arm 96 which is threaded at 98 at its outer end for the reception of counterbalance weights 100. The weights 100 are so selected and adjusted as to permit the apron assembly to pivot forwardly under its own weight toward the strand 26 about the shaft 88 and to rest on the strand with the desired pressure. Preferably this pressure should be sufficient to stop the twist from running up the thread beyond the bars 58 and 82. The apron is provided with a depending ear 102 (Fig. 4) which engages with a pin 104 on the operating rod 60 to limit forward movement of the apron assembly when the lower bar 58 is swung into its inoperative position.

The applicator is supported from the cap bar rod 40 so that it can be pulled forwardly to clear the rolls 14 and 18 and then swung upwardly and placed in the trough 42. To this end, the cap bar rod 40 is provided with a stationary arm 36 fixed against rotation to the rod 40. A link 38 is pivoted on the cap bar rod adjacent the fixed arm 36 and carries at its upper end a bracket 106 pivoted to the link 38 at 108 and fixed at its other end to the tube 34. A spring 110 has one end anchored to a pin 112 in the fixed arm 36 and its other end anchored at 114 on the link 38. Under the influence of the spring 110, link 38 is urged rearwardly into engagement with a stop pin 116 on the fixed arm 36. The applicator is thus urged rearwardly when in its operative position so that rounded noses 52 and 54 of side arm 48-50 are maintained in engagement with the shanks of the front draft rolls 12, 14. One fixed arm 36 may serve for two, or more, pivoted links 38.

Treating liquid is supplied to the tube 34 by means of flexible tubing 118 connected to the upper end of the tube. A needle valve 120 may be adjusted to control the rate of supply of liquid to upper bar 82.

Any liquid which may drip from the lower end of drip guard 80 is caught in the drip tray 44 which is mounted on the lappet 122 by means of a bracket 124. The rearward end of the drip tray 44 rests freely in a drip pan 126 supported on the roll beam 2. The tray 44 thus may be swung up with the lappet when it is necessary to move the lappet out of the way to remove or replace a bobbin.

The trough 42 is supported on the frame of the draft unit in any suitable way, as by means of arms 128. The trough 42 may be provided with a

drain tube 138 which conveniently may be a length of flexible tubing and may lead to the drip pan 128.

The operation of the device will be generally apparent from the foregoing description of its construction. The applicator is placed in operation by lifting it from the trough 42, rotating the knob 64 counterclockwise to move the lower bar 58 into the inoperative position shown in dotted lines in Fig. 3. The applicator is then pulled forwardly against the action of spring 114 and moved downwardly and inwardly until the noses 52 and 54 seat on the shanks of upper and lower rolls 12, 14. The knob 64 is then rotated clockwise to swing lower bar 58 upwardly into a generally horizontal position and into engagement with the strand 26. This adjusted position of bar 58 is predetermined by the position of the notch 66 on the rear face of the knob thus no particular care or attention on the part of the operator is required in placing the device in operation. The operator simply turns the knob 64 clockwise until he feels the detent 68 drop into notch 66, whereupon he knows that the lower bar 58 is in proper position.

The needle valve 128 is then opened to permit liquid to flow on to the upper surface of apron 84 and is adjusted to provide the desired rate of flow, which may be the amount of liquid which the drafting strand 8 will absorb without excessive drip. For doffing and donning or for piecing up a broken end, the applicator may be swung up into its rest position in tray 42 without adjusting the needle valve 128. Liquid flowing from the tube 34 will be caught by the trough and carried off through drain tube 138. The applicator is thus kept fully adjusted so that it may be quickly and conveniently put back in operation.

It will be observed that the treating liquid is applied to the strand at a point very closely adjacent the front drafting rolls 12, 14. In practice I have found this distance to be critical and that it must be less than an average staple length and preferably is a small fraction of a staple length.

The traveling roving strand thus is wetted after it has left the drafting zone but before it is twisted and this is accomplished without wetting the front drafting roll or any other part of the drafting mechanism. The strand is wetted before it has traveled more than a staple length from the drafting zone, and preferably before it has traveled more than a small fraction of a staple length from the drafting zone.

It may be necessary in changing from one type of yarn to another to adjust slightly the counterbalance weights 100 to obtain the proper pressure of the upper bar 82 on the traveling strand 26. This pressure should be such as to stop the twist, that is to prevent the twist imparted to the strand 26 by the spinning unit from traveling along the strand above the bars 58—82, but should not be so great as to cause sufficient friction to tend to break the yarn. The arrangement whereby the upper bar 82 is free to move toward and away from the lower bar 58 accommodates the normal slight variations in the thickness of the strand 26. In so moving, the upper bar travels along a path generally perpendicular to the strand 26, that is in a direction generally in the plane of the axes of the bars.

It will be appreciated that the process and apparatus of the present invention are useful in connection with doubling frames or in connection with frames for simultaneously twisting and

doubling strands of roving. The process and apparatus also can be used for treating filaments and are useful generally for application of various types of finishing materials such as sizing, flame-proofing, mildew-proofing, moth-proofing, water-proofing, and similar materials. Application of these finishes can be accomplished directly in the spinning frame without alteration of the standard spinning equipment other than by attachment of the device of the present application. The standard installed equipment thus does not have to be rebuilt and the substantial investment represented by spinning frames presently in operation is protected.

It will be appreciated that other types of spinning units than that shown and described herein, e. g., ring, filer or cap types of spinning units may be employed in connection with the present invention. Likewise the particular arrangement of drafting rolls shown and described is not an essential feature of my invention and my attachment may be used with any of the standing drafting frames.

I claim:

25. The method of spinning textile fibers which comprises drafting a traveling roving strand of textile fibers in a drafting zone to elongate the strand and reduce it to suitable size for spinning, applying a liquid treating medium to the drafted, dry, untwisted strand after it has left the drafting zone, and then immediately twisting the wetted, drafted strand.
30. The method of spinning textile fibers which comprises drafting a traveling roving strand of textile fibers in a drafting zone to elongate the strand and reduce it to suitable size for spinning, applying a liquid treating medium to the drafted, dry, untwisted strand after it has left the drafting zone but before it has traveled a staple length from the drafting zone, and then immediately twisting the wetted, drafted strand.
35. The method of spinning textile fibers which comprises drafting a traveling roving strand of textile fibers in a drafting zone to elongate the strand and reduce it to suitable size for spinning, applying a liquid treating medium to the drafted, dry, untwisted strand after it has left the drafting zone but before it has traveled more than a small fraction of a staple length from the drafting zone, and then immediately twisting the wetted, drafted strand.
40. The method of spinning textile fibers which comprises drafting a traveling roving strand of textile fibers in a drafting zone to elongate the strand and reduce it to suitable size for spinning, applying a liquid treating medium to the drafted, dry, untwisted strand after it has left the drafting zone but before it has traveled more than a small fraction of a staple length from the drafting zone, and then immediately twisting the wetted, drafted strand.
45. The method of spinning textile fibers which comprises drafting a traveling roving strand of textile fibers in a drafting zone to elongate the strand and reduce it to suitable size for spinning, applying a liquid treating medium to the drafted, dry, untwisted strand after it has left the drafting zone but before it has traveled more than a small fraction of a staple length from the drafting zone, and then immediately twisting the wetted, drafted strand.
50. The method of spinning textile fibers which comprises drafting a traveling roving strand of textile fibers in a drafting zone to elongate the strand and reduce it to suitable size for spinning, engaging the dry, untwisted, traveling strand by spaced members on opposite sides thereof after it has left the drafting zone, and supplying liquid directly to one of said members.
55. The method of spinning textile fibers which comprises drafting a traveling roving strand of textile fibers in a drafting zone to elongate the strand and reduce it to suitable size for spinning, wetting the drafted strand by engaging the dry, untwisted, traveling strand by spaced members on opposite sides thereof after it has left the drafting zone but before it has traveled more than a staple length from the drafting zone while maintaining one of said members in a wet condition, and twisting the wetted, drafted strand.
60. The method of spinning textile fibers which comprises drafting a traveling roving strand of textile fibers in a drafting zone to elongate the strand and reduce it to suitable size for spinning, wetting the drafted strand by engaging the dry, untwisted, traveling strand by spaced members on opposite sides thereof after it has left the drafting zone but before it has traveled more than a staple length from the drafting zone while maintaining one of said members in a wet condition, and twisting the wetted, drafted strand.
65. The method of spinning textile fibers which comprises drafting a traveling roving strand of textile fibers in a drafting zone to elongate the strand and reduce it to suitable size for spinning, wetting the drafted strand by engaging the dry, untwisted, traveling strand by spaced members on opposite sides thereof after it has left the drafting zone but before it has traveled more than a staple length from the drafting zone while maintaining one of said members in a wet condition, and twisting the wetted, drafted strand.
70. The method of spinning textile fibers which comprises drafting a traveling roving strand of textile fibers in a drafting zone to elongate the strand and reduce it to suitable size for spinning, wetting the drafted strand by engaging the dry,
75. The method of spinning textile fibers which comprises drafting a traveling roving strand of textile fibers in a drafting zone to elongate the strand and reduce it to suitable size for spinning, wetting the drafted strand by engaging the dry,

untwisted, traveling strand by spaced members on opposite sides thereof after it has left the drafting zone but before it has traveled more than a small fraction of a staple length from the drafting zone while maintaining one of said members in a wet condition, and twisting the wetted, drafted strand.

7. In a textile spinning frame including spaced pairs of drafting rolls adapted to be rotated at different speeds for progressively drafting a roving strand to reduce the same to a suitable size for spinning, the combination with said rolls of mechanism for supplying the liquid to dry drafted strand after it has left said rolls without wetting any of said rolls, comprising spaced members connected to said frame and engaging said drafted strand between them, and a conduit for supplying liquid to one of said members.

8. In a textile spinning frame including spaced pairs of drafting rolls adapted to be rotated at different speeds for progressively drafting a roving strand to reduce the same to a suitable size for spinning, the combination with said rolls of mechanism for wetting the drafted strand after it has left said rolls without wetting any of said rolls, comprising spaced members connected to said frame, engaging said drafted strand between them and positioned less than a staple length from said rolls, and means for supplying liquid to one of said members.

9. In a textile spinning frame including spaced pairs of drafting rolls adapted to be rotated at different speeds for progressively drafting a traveling roving strand to reduce the same to a suitable size for spinning, the combination with said rolls of mechanism for wetting the drafted strand after it has left said rolls without wetting any of said rolls, comprising spaced members connected to said frame and engaging said drafted strand between them, one of said members being mounted for free swinging movement toward and away from said traveling strand, and means for supplying liquid to one of said members.

10. An attachment for a spinning frame for applying a treating liquid to the traveling textile strand after drafting and before twisting comprising a bar having a rounded surface for engagement with the traveling strand in its operating position and mounted for movement into a position at right angles to said operating position, a second bar extending generally parallel to said first bar in its operating position and pivoted on said attachment for bodily swinging movement toward and away from said first bar, and means for conducting a treating liquid to said second bar.

11. An attachment for a spinning frame for applying a treating liquid to the traveling textile strand after drafting and before twisting, comprising a pair of spaced arms each having a rounded nose for engagement with the shanks of the front drafting rolls, a bar connected to and extending between said arms in an operating position and mounted for movement into a position at right angles to said operating position, a second bar extending between said arms generally parallel to said first bar in its operating position and pivoted on said attachment for bodily swing movement toward and away from said first bar, and means for conducting a treating liquid to said second bar.
